(57) **CLAIM**

The ornamental design for an electrical power unit for a work surface, as shown and described.

DESCRIPTION

FIG. 1 is a front, bottom, right side perspective view of an electrical power unit for a work surface; FIG. 2 is a front, top, right side perspective view thereof; FIG. 3 is a rear, top, right side perspective view thereof; FIG. 4 is a rear, bottom, right side perspective view thereof; FIG. 5 is a front elevation view thereof; FIG. 6 is a rear elevation view thereof; FIG. 7 is a top plan view thereof; FIG. 8 is a bottom plan view thereof; FIG. 9 is a right side elevation view thereof; and, FIG. 10 is a left side elevation view thereof.

The broken lines in the drawings are for the purpose of illustrating portions of the electrical power unit for a work surface that form no part of the claimed design.

1 Claim, 4 Drawing Sheets
